CLAIM

The ornamental design for a transparent shoe storage box, as shown and described.

DESCRIPTION

FIG. 1 is a front elevation view of a transparent shoe storage box showing our new design with a lid removed for clarity;

FIG. 2 is a right elevation view with a lid removed for clarity;

FIG. 3 is a top plan view with a lid removed for clarity;

FIG. 4 is a bottom plan view with a lid removed for clarity; and,

FIG. 5 is an isometric view of a transparent shoe storage box with a lid removed for clarity.

The broken lines shown in FIG. 5 are for illustrative purposes only and form no part of the claimed design.
